NENA E. STARR, OF TOWNSHIP 15, DOUGLAS COUNTY, NEBRASKA.

ELECTRIC SAD-IRON.

1,185,729.

Specification of Letters Patent.

Patented June 6, 1916.

Application filed August 28, 1914. Serial No. 859,088.

To all whom it may concern:

Be it known that I, NENA E. STARR, a citizen of the United States, residing in Township 15, in the county of Douglas and State of Nebraska, have invented certain new and useful Improvements in Electric Sad-Irons, of which the following is a specification.

The invention relates to an improvement in sad-irons and particularly to a sad iron 10 adapted to be electrically heated.

The main object of the present invention is the provision of means for controlling the heating element so that three distinct degrees of heat may be provided for, the construction involving a particular arrangement of heating contacts on the iron, and a special construction of socket for co-operation with said contact.

The invention in the preferred form of 20 details will be described in the following specification, reference being had particularly to the accompanying drawings, in which:—

Figure 1 is a perspective view of the improved sad iron. Fig. 2 is a vertical sectional view illustrating one disposition of the energizing means. Fig. 3 is a similar view showing another arrangement of such means. Fig. 4 is a diagrammatic view of 30 the heating circuits. Fig. 5 is a vertical sectional view through the socket.

The improved sad iron, in the details which are non-essential in their relation to the present invention, comprises usual hollow body 1, to which is removably secured in any appropriate manner the ironing block 2. The body is provided with a handle 3 and with feet 4 at one end thereof, on which the body may be supported while cooling or 40 while not in use.

Within the hollow body 1 above the block 2 are arranged the resistance elements, through the energization of which heat is imparted to the block 2. These elements are 45 preferably arranged between sheets of asbestos 5, and include two distinct resistance elements 6 and 7, which may be of any desired or known construction.

Projecting through one end of the top of 50 the body preferably adjacent the handle, are three contact posts 8, 9, and 10, and these posts are connected to the respective resistance elements in the following manner: the resistance element 6 is terminally connected 55 to the posts 8 and 9, while the resistance element 7 is terminally connected to the posts 8

and 10. The posts are insulated from the body as at 11, and project some distance above the upper surface of the body, as shown.

As an important part of the present invention, I utilize a socket member 12 preferably constructed of two sections 13 and 14 of non-refractory, insulating material. The socket is formed with spaced channels 15, 16, 60 and 17, in such relative positions as to permit their co-operation with the respective posts 8, 9, and 10. Contact blocks 18, 19, and 20 are arranged at the upper ends of the channels 15, 16, and 17, the blocks being 65 preferably extended lengthwise the channels in the form of contact sleeves 21. The upper end of the post 20 is slotted or longitudinally divided to receive one end of the switch blade 22 which is pivotally mounted 70 upon the central post 19. The switch blade is of L-form, the terminal of one arm being connected to an operating handle 23 which extends through a slot 24 in one section of the socket, so that the switch may be moved 75 to an operative position, as shown in Fig. 3, or to an inoperative position, as shown in Fig. 2. The switch forms the terminal of the conductors 25, 26, of any lighting circuit, said conductors within the socket being 80 led respectively to the posts 18 and 20, so that the post 19 is free of direct connection 85 in the circuit.

In use, with the parts arranged as described, it is obvious that with the switch in 90 operative position, as shown in dotted lines in Fig. 2, and the socket in engagement with all of the contact posts, the current passes through both resistances 6 and 7, developing the maximum heat. With the switch in 95 inoperative position, as shown in full lines in Fig. 2, the current passes through the resistance 7 only, developing a medium heat. If the socket is shifted, so as to engage the channels 15 and 16 with the contact posts 9 and 10, and the switch moved to operative 100 position, the current will pass through the resistances 6 and 7 in series with a developing of the minimum heat.

From the above construction, it will be understood that the improved flat iron is 105 electrically heated, in a manner to place at the disposal of the operator three distinct degrees of heat, through the simple control of a switch of the shifting of a socket.

What is claimed is:

An electrical heating means for sad irons 110

including three contact posts carried by the irons, two resistance elements arranged within the iron, one terminal of each of said elements being connected to one of the 5 posts, the remaining terminals of each of said elements being connected respectively to the remaining posts, in combination with a socket having a contact channel for each of said posts, energized blocks in two of said 10 channels, a normally non-energized block in the remaining channel, and a switch element

mounted for movement within the socket and at all times in electrical connection with the non-energized block, said switch being movable to connect the non-energized block 15 with one of the energized blocks.

In testimony whereof I affix my signature in presence of two witnesses.

NENA E. STARR.
